TAP CHANGING APPARATUS FOR
A TRANSFORMER

Masaaki Kagawa, Akira Watanabe, and Junichi Watanabe, Tokyo, Japan, assignors to Tokyo Shibaura Electric Co., Ltd., Kawasaki-shi, Japan, a corporation of Japan

Filed Nov. 27, 1963, Ser. No. 326,593

2 Claims. (Cl. 323—43.5)

This invention relates to an improved tap changing apparatus and more particularly to an arcless tap changer for a transformer and the like.

Although this invention can be applied for any transformer or reactor provided with a number of taps, for the sake of description, a tap changing apparatus as applied to a transformer mounted on an alternating current electric vehicle will be explained in the following.

With recent progress in electric railway systems alternating current electric cars or locomotives have become widely used. Generally, in alternating current railway systems the cost of initial installation of machines and apparatus to be installed on the ground, such as those in substations is lower whereas the cost and size of the control apparatus mounted on the vehicle are higher when compared with direct current system. More particularly, in an alternating current railway car the speed of the car is controlled by varying the voltage applied to traction motors by changing taps of a main transformer mounted on the car, and it is necessary to increase the number of taps to decrease the voltage difference between adjacent taps in order to gradually and smoothly start and accelerate the car.

Most of the prior tap changers have employed a combination of a plurality of contacts having sufficient electric power interrupting ability which are operated in a predetermined sequence to interrupt the short circuit current flowing between adjacent taps when on-load tap changing is effected. With such a prior arrangement, the main switch, such as an air circuit breaker is operated to interrupt the motor current at each time when the tap changer operates from one tap to the next so that it is difficult to gradually and smoothly start the car. Moreover as the contacts of the tap changer switch are damaged by severe electric arc their usable life is short and requires large labor and cost of maintenance.

In order to eliminate the above mentioned disadvantages an arrangement has been proposed utilizing a mercury arc electric valve and mechanical switches wherein initiation and interruption of the current are effected by the electric valve and the mechanical switches are used to change electrical connections to different taps in no current condition. However, with such an arrangement use of a mercury arc electric valve results in the increase of the size and cost of the tap changing apparatus thus rendering it difficult to mount them in a narrow space available on a car or locomotive.

Accordingly, in prior alternating current electric cars, tap changers with mechanical contacts were generally used, but owing to frequent failure of such contacts due to electric arc, development of an arcless tap changing apparatus has long been desired.

Thus it is the principal object of this invention to provide an arcless tap changing apparatus for transformers and reactors.

Another object of this invention is to provide an arcless tap changing apparatus utilizing semiconductor switches such as silicon controlled rectifier elements.

A more specific object of this invention is to provide an improved tap changing apparatus particularly suitable for use in alternating current vehicles, which is small size and light weight and yet can provide gradual and smooth acceleration of the electric car.

2

Still a further object of this invention is to provide an improved method of changing taps of a transformer and the like which can substantially increase the effective number of voltage steps by using a given number of taps and semiconductor switches of relatively small capacity.

In accordance with this invention these and other objects are attained by providing an electric transformer including a winding provided with a plurality of voltage adjusting taps and connected to be energized from a source of alternating current, a load supplied with a variable voltage from said transformer, a plurality of first contactors each associated with one of said taps of said transformer winding to connect said one tap to said load, a pair of branch circuits each including a reactor winding and a second contactor for connecting alternate ones of said first contactors to said load, a third contactor connected across terminals of said reactor windings which are close to said transformer winding, said third contactor being arranged to be closed when one of said taps is selected but opened during tap changing operation, a pair of semiconductor switches connected in reverse parallel relation across the opposite terminals of said reactor windings to pass positive and negative half cycles, respectively of said alternating current when said second contactor is operated during tap changing operation.

According to the method of this invention a suitable controller is provided to effect the following sequential steps of connecting the first tap to the load through said pair of parallel branch circuits each including a reactor winding, disconnecting one of said branch circuits from said load and connecting it in parallel with the other branch circuit through said pair of semiconductor switches, turning off said semiconductor switches to disconnect said first branch circuit from said load, connecting said other branch circuit between the second tap and said load through said semiconductor switches while limiting the short circuit current flowing between said first and second taps by said reactor windings, connecting said other branch circuit directly to said load thereby to supply thereto a voltage intermediate of the voltages at said first and second taps, connecting said first branch circuit to said load through said semiconductor switches, disconnecting said first branch circuit from said first tap, connecting said first branch circuit in parallel with said second branch through said semiconductor switches and connecting said first branch circuit directly to said load thereby to energize it by the voltage at said second tap through said pair of branch circuits.

Thus, according to this invention taps can be changed without producing any objectional electric arc at various contactors and without actually interrupting the load circuit. Moreover, semiconductor switches of relatively small capacity can be utilized because they are required to carry the load current only during intervals during which the taps are changed.

The subject matter of the invention is particularly pointed out and distinctly claimed in the concluding portion of the specification. The invention, however, both as to organization and method of practice, together with further objects and advantages thereof, may best be understood by reference to the following description taken in connection with the accompanying drawings, in which:

FIG. 1 shows a circuit diagram of an arcless tap changing apparatus constructed according to the principle of this invention;

FIG. 2 shows a sequence table of the respective contactors of the tap changing apparatus shown in FIG. 1; and

FIG. 3 shows various connections of a portion of FIG. 1 at the successive steps of tap changing operation.

Referring now to the accompanying drawings which illustrate one embodiment of this invention as applied to an alternating current locomotive, in FIG. 1 is shown a transformer T_r having a primary winding **10** with one terminal connected to a trolley wire via an air circuit breaker ACB and a pantograph PT and the other terminal grounded and a secondary winding **12** provided with a plurality of taps **13**, **14**, **15** and **16**. A load **17**, such as the traction motors of an electric vehicle, is connected across the secondary winding **12** to be supplied with a variable voltage through a tap changing arrangement embodying this invention to be explained hereinafter. Thus, each of the taps **13**, **14**, **15** and **16** is connected to one terminal of each of contactors K_1 , K_2 , K_3 and K_4 and the common junction between contacts K_1 and K_3 is connected to a conductor **18**. Similarly, the right hand terminals of the contactors K_2 and K_4 are connected to a conductor **19**. A pair of windings **20** and **21** wound upon a common magnetic core **22** of a reactor **23** are respectively connected in conductors **18** and **19**. Between the left hand terminals of the reactor windings **20** and **21** which are close to the transformer taps is connected a contactor T_0 which is operated as will be explained later in more detail. Opposite terminals of the reactor windings **20** and **21** are connected to one terminal of the load **17** respectively through contactors T_2 and T_1 and the other terminal of the load is connected to the lower terminal of the transformer secondary winding **12**. A pair of semiconductor switches, such as silicon controlled rectifiers **24** and **25** (hereinafter designated as SCR) are connected in parallel but with opposite polarities across conductors **18** and **19** between said reactor **23** and said contactors T_1 and T_2 . As shown in the drawings, the gate electrode of the SCR **24** is connected to its anode via a contact T_{11} while the gate electrode of the SCR **25** is connected to its anode via a contact T_{12} .

The operation of the tap changing apparatus illustrated in the accompanying drawings is as follows: At first it is assumed that the load or traction motors **17** are to be connected to the lowest tap **13** of the secondary winding **12** to start them gradually. Although not shown in the drawings it should be understood that a suitable controller is provided for the electric vehicle for opening and closing contactors or contacts K_1 , K_2 , K_3 , K_4 , T_0 , T_1 , T_2 , T_{11} and T_{12} according to a predetermined sequence as will be described hereinafter.

As shown by a sequence table of FIG. 2, when the controller is advanced to its first notch **1** contactors K_1 , T_0 , T_1 , T_2 , T_{11} and T_{12} are closed. At the same time the air circuit breaker ACB in the primary circuit of the transformer T_r is closed to energize it from the trolley wire. The circuit established at that time between the tap **13** and the load **17** is shown by FIG. 3-1. In this state all contactors are closed whereby the load current flows to the load through parallel branches, one including the contactor T_0 , the conductor **19**, the reactor winding **21** and the contactor T_1 , and the other including the reactor winding **20**, the conductor **18** and the contactor T_2 . In this case, reactor windings **20** and **21** operate to equalize the amount of current flowing these branches, as is well known in the art. When advancing the controller from the first notch **1** to the second notch **2** of FIG. 2, it sequentially passes five positions **1a** to **1e** inclusive. In the position **1a**, the contactor T_1 is opened as shown by FIG. 3-1a. If it is assumed that the contactor T_1 is opened during a positive half cycle of the voltage appearing at the tap **13**, then a current will flow through the gate electrode of the SCR **24** thus turning it on. On the contrary if the contactor T_1 is opened during the negative half cycle the other SCR **25** will be turned on to by-pass the load current around the contactor T_1 . In this manner, the contactor T_1 can be opened without producing any electric arc, and in this condition the load current is divided equally between two reactor windings through a pair of silicon controlled rectifiers **24** and **25**.

At the end of the positive half cycle the SCR **24** turns off and similarly at the end of the negative half cycle the SCR **25** turns off. The current flowing through the branch including the contactor T_0 , the reactor winding **21**, the conductor **19** and the silicon controlled rectifiers **24** and **25** is reduced to zero whereby the contactor T_0 can be opened without accompanying any arcing. Thus, the controller is advanced from position **1b** to **1c** in FIG. 2 to open the contactor T_0 . The connections at the respective controller positions **1b** and **1c** are schematically shown by FIGS. 3-1b and 1c. As shown by FIG. 3-1c, the load current then flows only through the branch including the contactors K_1 , K_2 and the reactor winding **20**. The controller is then advanced from the position **1c** to **1d** as shown in FIG. 2. Then, the contactor K_2 is closed to connect the reactor winding **21** to the second tap **14**. However, this contactor K_2 can be closed without any arcing because both of the silicon controlled rectifiers **24** and **25** are in off condition. This condition is schematically shown by FIG. 3-1d. When the controller is advanced from the position **1d** to the position **1e** of FIG. 2, contactors T_{11} and T_{12} will be closed whereby gate currents are supplied to the silicon controlled rectifiers **24** and **25** during positive and negative half cycles, respectively, to turn them on. This condition is shown by FIG. 3-1e. The short circuit current flowing between taps **13** and **14** during this condition through the contactor K_1 , conductor **18**, reactor winding **20**, silicon controlled rectifiers **24** and **25**, conductor **19**, reactor winding **21** and conductor **19** is reduced to a low value by the action of the reactor **23**, whereas the voltage applied to the load **17** is increased to the mean value of those appearing at taps **13** and **14**. The controller is then advanced from the position **1e** to the second notch **2** of FIG. 2. Then the contactor T_1 will be closed to establish a circuit as shown in FIG. 3-2. Inasmuch as the forward voltage drop of silicon controlled rectifiers **24** and **25** is very small, the contactor T_1 can be closed without any arcing. Thus, it will be noted that at the second notch **2**, a mean voltage of those appearing at the taps **13** and **14** is impressed upon the load **17**. In order to further increase the voltage supplied to the load until it becomes equal to the voltage of the tap **14**, the following procedures are required. While such a voltage can be obtained at the third notch of FIG. 3, additional five steps or positions are necessary between notches **2** and **3**. More particularly, as will be clear from the sequence table shown in FIG. 2, at the position **2a**, the contact T_2 is opened to establish a circuit as shown by FIG. 3-2a. As already pointed out, as soon as the contactor T_2 is opened, silicon controlled rectifiers **24** and **25** will be turned on to permit the contactor T_2 to open without arcing. Movement of the controller from the position **2a** to **2b** of FIG. 2 will result in the opening of contactors T_{11} and T_{12} to turn off the silicon controlled rectifiers **24** and **25**. As the result the branch through the conductor **18** is interrupted so that the load current will be supplied to the load **17** through the remaining branch including the contactor K_2 , conductor **19**, reactor winding **21** and the contactor T_1 as shown by FIG. 3-2b. Thus, the contactor K_1 can be opened without any arcing. In other words, by advancing the controller from the position **2b** to the position **2c**, the contactor K_1 will be opened to establish a circuit as shown by FIG. 3-2c to feed the load **17** under higher voltage supplied from the tap **14** via the contactor K_2 , conductor **19**, reactor winding **21** and the contactor T_1 . At this time the contactor T_0 can be closed without any arcing at the position **2d** of FIG. 2 to establish a circuit as shown by FIG. 3-2d. Then the controller is further advanced to the position **2e** to close the contacts T_{11} and T_{12} in the gate electrode of SCR, thus establishing a circuit indicated by FIG. 3-2e. Thus, the silicon controlled rectifiers **24** and **25** will be turned on to equally divide the load current between reactor

windings 20 and 21. Thereafter, the controller is advanced to the notch 3 to close the contactor T_2 to short circuit the silicon controlled rectifiers by means of the contactors T_1 and T_2 . Thus, normally these rectifiers do not carry large load current and the voltage impressed upon the load 17, that is, the traction motors are increased to the voltage at the tap 14.

The process of changing the connection from tap 14 to tap 15 for further increasing the load voltage is shown by the steps from the notches 3 to 5 of the sequence table shown in FIG. 2, the sequence of opening and closing various contactors being the same as described above in connection with FIG. 3. Similarly when the controller is advanced from the notches 5 to 7 through the notch 6, the connection will be changed from the tap 15 to 16, thus applying higher voltage to the load.

For reducing the load voltage or decelerating the vehicle, the controller is returned from the highest notch 7 or any intermediate notch back to the first notch 1. Then various contactors will be operated in a sequence just opposite to that described above in connection with acceleration to decrease the load voltage to that of the tap 13. When the contactor is returned to the off position, the main circuit breaker ACB is tripped to interrupt the load circuit.

From the above description it will be clear that this invention provides a novel tap changing apparatus which has relatively simple construction, long operating life with minimum cost of maintenance and can operate various contactors or contacts without producing any harmful electric arc for changing transformer taps. In order to operate the contactors in a tap changing circuit without arcing, heretofore it has been the practice to open the main circuit breaker ACB or a circuit breaker provided at the terminal of the load, but in such a load as electric vehicles, the motor current is interrupted, thus causing large shock whenever the circuit breaker is opened. On the contrary, since in accordance with this invention the circuit breaker ACB is operated only for the initial closure of the load circuit and final interruption thereof and is not operated for effecting tap changing it will be obvious that the electric vehicles can be accelerated or decelerated very smoothly. Moreover, semiconductor switches are required to carry the load current only during short intervals at the time of tap changing so that semiconductor switches of relatively small capacity and hence of low cost can be used.

While this invention has been described in connection with a preferred embodiment thereof it will be understood that various changes and modifications will occur to those skilled in the art without departing from the true spirit and scope of the invention as defined by the appended claims.

What is claimed is:

1. Tap changing apparatus comprising a combination

of an electric transformer including a winding provided with a plurality of voltage adjusting taps and connected to be energized from a source of alternating current, a load supplied with a variable voltage from said transformer, a plurality of first contactors each associated with one of said taps of said transformer winding to connect said one tap to said load, a pair of branch circuits each including a reactor winding and a second contactor for connecting alternating ones of said first contactors to said load, a third contactor connected across terminals of said reactor windings which are close to said transformer winding, said third contactor being arranged to be closed when one of said taps is selected but opened during tap changing, a pair of semiconductor switches connected in reverse parallel relation across the opposite terminals of said reactor windings to pass positive and negative half cycles, respectively of said alternating current when said second contactors are operated during tap changing operation.

2. Method of changing taps of a transformer having a plurality of taps comprising the steps of connecting the first tap to a load through a pair of parallel branch circuits each including a reactor winding, disconnecting one of said branch circuits from said load and connecting it in parallel with the other branch circuit through a pair of semiconductor switches which are connected in parallel but in opposite polarities, turning off said first branch circuit from said load, connecting said other branch circuit between the second tap and said load through said semiconductor switches while limiting the short circuit current flowing between said first and second taps by said reactor windings, connecting said other branch circuit directly to said load thereby to supply to said load a voltage intermediate of the voltages at said first and second taps, connecting said first branch circuit to said load through said semiconductor switches, disconnecting said first branch circuit from said first tap, connecting said first branch circuit in parallel with said second branch circuit through said semiconductor switches and connecting said first branch circuit directly to said load thereby to energize it by the voltage at said second tap through said pair of branch circuits.
